BOILER FEEDING APPARATUS

Romualdo Bertoluzzi Regazzi, Rua Cacapava 110,
Rio de Janeiro, Brazil

Filed Apr. 25, 1961, Ser. No. 105,349

Claims priority, application Brazil May 2, 1960

1 Claim. (Cl. 122—451)

A boiler is more efficient and economical when it is supplied with pre-heated water rather than cold water. That is to say, the higher the temperature of the feeding water introduced in the boiler, the more efficient the boiler becomes. However, in some cases, injectors do not work satisfactorily when performing hot water suction, and also pumps commonly used do not function efficiently when the temperature of the water is too high.

On the other hand, if steam is used in a simple, closed and high container holding cold water, to force water into the boiler, the steam coming in contact with the cold surface of the water will condense and cause a fall in the boiler pressure. Soon thereafter, when the heat of the steam warms the water to a sufficiently high temperature, the pressure will be normal and the water forced into the boiler will function more efficiently.

Accordingly, the present invention provides an apparatus and method for boiler feeding, which is simple, effectual and economical; which works safely and much better than apparatus now in use; and the controlled temperature of the water to be introduced in the boiler permits dispensing completely with the injectors, pumps, or the like.

A preferred and practical form of the invention is shown in the accompanying drawing, in which:

FIG. 1 is a diagrammatic view of the improved system.

FIG. 2 is a diagrammatic sectional view taken on the line 2—2 of FIG. 1.

Referring to the drawing, the vertically disposed boiler 1, heated by a suitable burner or the like (not shown), has a horizontal flue 2 at its lower end to conduct the heated gases from beneath the boiler to the chimney 3 which discharges into the atmosphere. The flue 2 and the chimney 3 contain a coil C which is a part of the heating and circulating system. The chimney 3 is surrounded by a water jacket 5' having a float valve 4 at its upper end for controlling the flow of cold water into the main water jacket 5 of the boiler as shown by the arrows. It will thus be seen that the boiler, heating chamber, and stack or chimney are all surrounded by communicating water jackets. The valve 6 is controlled by a float 7 to automatically maintain the fluid level in the boiler. As shown by dotted lines 7a in FIG. 1, the water level control device may be placed on the outside of the boiler jacket if desired.

A tank 8 is provided to collect water from the jacket 5, through the said valve 6, and also collect water produced by the condensation of the used steam that comes through the valved conduit 10a. When valve 6 is closed, check valve 9 permits free passage of water through conduit 9a in the direction of the arrow to the high part of the jacket 5 itself, keeping the water in constant circulation and increasing its temperature.

Conduit 10a and valve 10 permit water from steam already used to be collected in the feed tank 8 while check valve 11 passes the hot water from the feed tank 8 to the tank 12, following the direction of the arrow and preventing its passage in the opposite direction, as will later appear.

Hot water and steam under pressure in tank 12 permit raising of the highly heated water up to the desired height, and into the upper feed tank 21, by forcing its

2

passage through check valve 17 and into the heating coils C, thus increasing the temperature of the feeding water.

An alternate feed tank 12a, identical to feed tank 12, is installed whenever continuous feeding of the boiler is desired. This tank fills itself with hot water while container 12 empties itself and vice-versa, obtaining continuous rise of the feeding water. The boiler's steam exhaust conduit 13a is controlled by valve 13 such that excess steam goes straight to the tank 12 through entrance control valve 14.

There is included in tank 12 an automatic device including two valves 15, 16 actuated by a float, so that, as the valve 15 is opened, the valve 16 is closed, and vice-versa. As previously indicated, a check valve 17 below tank 12 permits passing of hot water from said tank to heating coils C. Thus, the steam pressure entering tank 12 forces the water therein to flow out through valve 17 and into heating coils C. When the water has been expelled from tank 12, the control members 15 and 16 operate to cut off the inflowing steam and the valve 11 opens the conduit from tank 8 to allow the water therein to flow into tank 12 through valve 11 to refill the tank. A control valve 18, operated by steam pressure, permits excess steam to pass from tank 12 to feed tank 8.

The coils C or the like are installed in the heating chamber 2 and also in the chimney 3, to derive the benefit from the heat of gases produced in the boiler and to raise the temperature of the feeding water. The check valve 20 at the upper end of the coils C permits passage of hot water therefrom to the main upper feed tank 21, located above the water level of the boiler, following the direction of the arrows and obstructs passage of steam in the opposite direction. Said feed tank 21 containing hot water and steam under pressure above the level of the boiler water, permits the efficient and fast insertion of feeding water in the boiler even if this water is highly heated.

A second or alternate feed tank 21a, identical to tank 21, may be installed whenever continuous feeding of the boiler is desired. This tank fills itself with hot water, while feed tank 21 is emptied and vice-versa, permitting continuous insertion of the feeding water into the boiler. The arrangement and purpose of the tanks 21, 21a is the same as that of tanks 12, 12a; however, the tanks serve different purposes. Tank 12 raises the heated water up to the desired height while tank 21 feeds the heated water into the boiler.

A control valve 22 permits the passing of the vapor which comes from the boiler to the main upper feed tank 21, while an automatic float actuated valve 23—24, identical to valve 15—16, controls passage of water from feed tank 21 to the boiler. Steam pressure inside of tank 21 closes check valve 20 and equalizing the pressure between tank 21 and the boiler will force the water in tank 21 to flow downwardly into the boiler by gravity through valves 25 and 26. The valve 26 is a check valve and obstructs passage of steam from the boiler to tank 21. Also, a control valve 28 permits direct connection of the water jacket 5, 5' with the heating apparatus C when the flow of water is interrupted in the feed tank 12.

The valve 29 permits passage of water from the heating coils C to the upper part of the water jacket 5' when flow of water in the feed tank 12 is interrupted, thereby maintaining continuous water circulation and increasing its temperature. The check and control valve 30 permits steam exhausted from feed tank 8 to pass to jacket 5 at its upper end, prevents the rise of pressure inside the feed tank 8, thus permitting the entry of the returning water into said tank and also gaining the heat of the steam.

When manual installation is preferred, the automatic apparatus 7 and the automatic valves 15—16 and 23—24

will be omitted. The graduated valve 6 will be controlled by hand and the discharge of water from the feed tanks 12 and 21 will be obtained by putting the valves 14, 18, 22, and 27 in motion by hand. In this installation, the feed tanks 12 and 21 will be provided for example with glass indicators such as the ones used in the boilers to indicate the level of the water inside them permitting accurate control by the operator.

Whenever continuous feeding of the boiler is desired, two more alternating feed tanks 12A and 21A will be installed. These alternating tanks are identical to feed tanks 12 and 21, and can be joined to them and will work in a way such that, while one is receiving hot water, the other is discharging and vice versa, thus constantly maintaining the cycle of feeding the boiler.

The general operation of the system will now be described.

The cold water to supply the boiler enters jacket 5, 5' where it absorbs the heat radiating from the chimney 3, the conduit 2, and the boiler 1. Hot returning water, already partly heated, is gathered in feed tank 8 and injected by action of gravity into the feed tank 12 containing hot water and steam under pressure. Steam under pressure from the boiler passes through the conduit connecting the upper part of the boiler and the upper part of tank 12 through control valves 13 and 14 to the feed tank 12. The already partly heated water in tank 12 is forced by the incoming steam pressure to pass through check valve 17 and heating coils C, where, by absorbing more heat, the temperature of the water is raised and it is injected in the alternating feed tank 21. The tank 21 is located above the level of the water inside the boiler itself inside the feed tank 21 and by the action of gravity, the very highly heated water is introduced in the boiler in a sufficient quantity and at a desired temperature.

From the foregoing, it will be recognized that the advantages of applicant's invention are: (1) providing means (jacket 5, 5') for utilizing heat normally radiated from the boiler, flue and chimney when the boiler is fired to thereby increase the operating efficiency of the boiler; (2) eliminating injectors or pumps commonly used to circulate the heated water by using in place thereof the steam pressure generated by the apparatus and directing the steam to supply tanks (8, 12, 21); and (3) by appropriate control valves (14, 18, 15, 16 for tank 12) (20, 22, 27, 23, 24 for tank 21), operated either manually or

automatically, the steam and water pressure in the supply tanks is equalized, causing the water therein to be evacuated and circulated through the system into the boiler. The purpose of tank 12 is to raise the heated water up to the desired height, whereas tank 21 injects controlled amounts of water into the boiler.

I claim:

In a steam boiler having side walls and a heating space, a chimney, and a flue pipe connecting said heating space and chimney, apparatus for continuously heating and recirculating water introduced into said boiler, said apparatus comprising, in combination, a water receiving jacket surrounding the walls of the boiler, the flue pipe, and the chimney, valve means controlling entry of unheated water into said jacket, a receiving tank in communication with said jacket at a point remote from said valve means, a first feed tank disposed lower than said receiving tank and connected thereto, heating coils disposed in the heating space in said boiler and in said flue and chimney, means connecting the top of said first feed tank to the top of said boiler to permit the introduction of steam into said first feed tank, means connecting the lower portion of said first feed tank to said heating coils, control means within said first feed tank to alternately permit the introduction of steam and water to said tank, a second feed tank located at a level higher than the top of said boiler, said tank communicating with said heating coils to receive heated water therefrom and also communicating with the upper portion of said boiler to introduce heated water therein, an incoming valved steam conduit connecting the upper part of said boiler with said second feed tank, an outgoing valved steam conduit connected to the upper portion of said second feed tank and leading to the top of said receiving tank, and control means regulating the flow of water into said second feed tank and into said boiler and also controlling the flow of steam from said boiler into said second feed tank.
